(57) CLAIM

The ornamental design for a magnetic pill case as shown and described.

DESCRIPTION

FIG. 1 is a top front perspective view of a magnetic pill case showing the claimed design according to an embodiment;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is an exploded top front perspective view thereof in a position where individual surrounding compartments are separated from the base; and,

FIG. 9 is a top front perspective view thereof in a position where individual surrounding compartments have each been inverted on the base.

The broken lines in the drawings indicate portions of the magnetic pill case that form no part of the claimed design.

1 Claim, 7 Drawing Sheets
